UNITED STATES PATENT OFFICE.

HENRY C. STOLL, OF NEW YORK, N. Y., ASSIGNOR TO AMERICAN CAN COMPANY, OF NEW YORK, N. Y., A CORPORATION OF NEW JERSEY.

AUTOMATIC STOP FOR PRESSES.

Application filed August 8, 1921. Serial No. 490,508.

This invention relates in general to presses such as are generally used in operating upon sheet metal blanks and the like, and refers more particularly to an automatic 5 stop device for machines of this character adapted to operate in a predetermined event.

A principal object of the invention is the provision of an automatic stopping device which is sensitive and accurate in operation 10 and adapted to function with certainty to stop the action of the machine under conditions likely to cause breakage of parts of the machine or damage thereto.

A particular object of the invention is the 15 provision of a device of this character adapted to operate in the event of the accidental depositing in the press of a greater number of blanks than the operating mechanism is able to accommodate with distortion or breakage thereof.

A further object of the invention is the 20 provision of a safety device of the character described which is adjustable in such manner as to be operable in case of the presence of any predetermined number of blanks.

Still another object of the invention is the provision of a mechanism for accomplishing the foregoing objects which in no 25 way interferes with the normal operation of the machine, and which is simple in construction and adapted to effectively and efficiently cooperate with the regularly employed parts of a machine of this general 30 character.

Numerous other objects and advantages of the invention will be apparent as it is better understood from the following description, which, taken in connection with 35 the accompanying drawings, discloses a preferred embodiment thereof.

Referring to the drawings:

Figure 1 is a side elevation of a double action draw press upon which my invention 40 is employed;

Fig. 2 is an enlarged plan view partly in section taken substantially on the line 2—2 of Fig. 1;

Fig. 3 is an enlarged vertical section taken 45 substantially on the line 3—3 of Fig 1; and

Fig. 4 is an enlarged detail section taken substantially on the line 4—4 of Fig. 2.

Fig. 5 is a vertical sectional view taken on a plane at right angles to the plane of

Fig. 4 and illustrating the parts 18, 19, 54 55 and 54'.

For the purpose of illustrating my invention I have shown in the drawings a press having a pedestal support 11, a body frame 12 and operating mechanism generally indicated by the reference numeral 13. It is not deemed necessary to describe this mechanism in detail since it forms no part of my invention, and it will suffice to state that said mechanism is set in operation by means of 60 a foot pedal or treadle 14 and a connecting lever 15. The die members 16 and 17 function in a well known manner to draw or form can covers or other desired articles from blanks successively fed thereto.

In the ordinary course of operation of a machine of this character it sometimes happens that more than one blank is accidentally deposited upon the lower die member with the result that upon the next subsequent action of the die parts the crank shaft or some other part of the machine is broken or damaged by the strain which the extra thickness of metal imposes upon said parts. I have, therefore, provided mechanism, to be hereinafter described, which serves to automatically stop the operation of the machine when more than one, or any predetermined number of blanks, are fed to the bottom die members. This mechanism 75 includes a detector rod 18 which extends upwardly through a pressure screw 19, a pressure rubber 21, a pressure ring 22 and the die bottom 23.

In operation the blanks are fed onto the die member 17 and over an aperture 24 therein. The member 17 rests upon a sub-bolster 25 which has screw threaded supporting engagement with the pressure screw 19. Upon operation of the die parts the blank 26 is formed, as indicated in Fig. 4, and in the usual course is ejected without stopping the action of the machine. In case two blanks are present, however, the rod 18 is actuated to set in motion the parts of the stopping device, to be hereinafter described, thereby protecting the machine from the damage which probably would ensue from continued operation. It will be understood that a certain amount of play is allowed at the point 95 27 between the sub-bolster 25 and the die bottom or plunger 23. This, with the resiliency of the pressure rubber 21, prevents any 100 105

harmful results from the operation of the die parts upon two blanks and is sufficient also to permit operation of the detector rod by increased pressure thereon due to the double thickness of the metal between the die parts. The upper end of the rod 18 is provided with a shoulder 28 upon which the die bottom 23 is adapted to operate in the event mentioned.

10 It will be noted that the lower end 29 of the detector rod rests upon a set screw 31 which extends through a lug 32 protruding from a lever 33, this lever being supported by a pin 34 extending through bearings 35 projecting from a bracket 36. Secured in the opposite side of the bracket 36 by means of a pin 37 is a treadle lift lever 38 having one arm 39 to which a connecting rod 41 is secured by means of a cotter pin 42; and this 15 rod has connection, adjustable by the set screw 43, with the treadle lever 15. The lift lever 38 has also a vertical arm 45 carrying at its lower end a release pin 46 cut away in its upper portion to provide a 20 face 47 adapted to cooperate with a pawl 48 extending from the lever 33 to which it is secured by means of a screw 49. The lever 33 has a depending socket projection 51 for the reception of a release spring 52, one end 25 of which bears against the vertical arm 45 of the lever 38 and is held in place by means of a projection 53 extending into the spring. It will be seen that in this manner constant pressure is exerted upon the arm 45 tending 30 to lift the treadle 14 through the connecting rods 41 and 15.

Depression of the foot pedal or treadle 14 by the foot of the operator serves to start the operation of the machine and also locks 40 the automatic stopping mechanism just described by forcing the locking face 47 of the pin 46 behind the cooperating face of the pawl 48. The action of the machine may now continue until stopped by hand 45 through pulling downwardly upon the adjusting screw 31, or by the automatic action of my stopping device.

It will be observed that the lever 33 is 50 pivotally mounted upon the pin 34 and that downward movement of the rod 18 serves to raise the pawl 48 projecting from the end of the lever opposite that carrying the adjusting screw 31, thereby permitting the tension of the spring 52 to move the lift lever 38 about its axis on the pin 37, lifting the control pedal 14 and throwing the machine out of operation. It will be readily 55 understood that by adjustment of the screw 31 the amount of play between the parts 23 and 25 may be coordinated with the action of the pawl 48 so that the stop mechanism may be caused to operate by a greater or less number of blanks in the die parts. Thus, it may be so adjusted that a single 60 thickness of metal would cause operation of

said mechanism or so that several thicknesses would be required.

The rod 18, it will be seen, is under constant upward stress through the force of the spring 52, and positive pressure thereon is required to release the pawl 48. Sliding movement of said rod is limited by a screw 54 screwed into the part 19 and having its inner end engaging in a groove or recess 54' formed in one side of the rod 18, as best 75 seen in Fig. 5, and the lower pressure sustaining members are suitably retained within the supporting rings 56 and 57, or in any preferred manner. 55 is a hole through the lower part of the screw 19 wherein a tool 80 or spanner may be inserted to turn and adjust said screw.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, 90 the form hereinbefore described being merely a preferred embodiment thereof.

I claim:—

1. An emergency stopping device for presses and the like, comprising a die bottom 95 and pressure sustaining members, a detector rod extending therethrough and having an end in position to be operated by pressure of a predetermined number of blanks in the press and means operated by said detector 100 rod for automatically terminating the action of the machine.

2. An emergency stopping device for presses and the like, comprising a die bottom and pressure sustaining members, a detector rod extending therethrough and having an end in position to be operated by pressure of a predetermined number of blanks in the press, an operating control member adapted to be locked in position 105 to cause continued action of the machine, and means operated by movement of said detector rod for releasing said control member and terminating the action of the machine.

3. An emergency stopping device for presses and the like, comprising a die bottom and pressure sustaining members, a detector rod extending therethrough and having an end in position to be operated by pressure 110 of a predetermined number of blanks in the press, an operating control member 14 adapted to be locked in position to cause continued action of the machine, and means operated by movement of said detector rod for releasing said control member and terminating the action of the machine, said means comprising a spring pressed lever 38 connected with said control member, a pawl 48 normally holding said lever in locked position 115 120 125 130 135

while the machine is operating, and a release member 33 carrying said pawl and operable by movement of said rod.

4. An emergency stopping device for presses and the like, comprising bottom die and pressure sustaining members under the bottom die, a rod extending through said members and operable by pressure of a predetermined number of blanks in the press 10 and means operated by said rod for automatically terminating the action of the machine.

5. An emergency stopping device for presses and the like, comprising means for 15 sustaining blanks, means extending into position on the blank-sustaining means to be automatically influenced by the pressure of said blanks, and mechanism comprising a holding and releasing pawl operated by said 20 last mentioned means for terminating the action of the machine in the event of an excessive number of blanks being fed thereto.

6. An emergency stopping device for presses and the like, comprising a female die resting upon pressure absorbing members, means extending through said die, said means being actuated by a predetermined excess of pressure upon said die, said means acting upon mechanism for automatically 25 stopping the press.

7. An emergency stopping device for presses and the like, comprising means for sustaining blanks, detecting means extending into position to be automatically influenced by an excessive number of said blanks, an 30 operative control adapted to be set to cause continued operation of the machine, and mechanism comprising a holding and releasing pawl and a spring which is confined under pressure by said pawl, operated by said 35 detecting means and moving said control from operative position whereby to terminate the action of the machine.

HENRY C. STOLL.
